(57) **CLAIM**

I claim an ornamental design for a trigger for projectile weapon, as shown.

DESCRIPTION

FIG. 1 is a perspective view of a trigger for projectile weapon of my new design;

FIG. 2 is a front view thereof;

FIG. 3 is an elevational view from one side thereof;

FIG. 4 is top view thereof;

FIG. 5 is an elevational view from the other side thereof;

FIG. 6 is a bottom view thereof;

FIG. 7 is a rear view thereof; and,

FIG. 8 is a perspective view of the rear thereof.

The shading in the figures show contour, not surface ornamentation, and form no part of the claimed design.
